RECLOSED CARTON

Edward G. Farrell, Portland, Oreg., assignor of one-half
to E. W. De Koning, Portland, Oreg.

Application June 27, 1958, Serial No. 745,042

6 Claims. (Cl. 229—17)

This invention relates to an improvement in packages or cartons, and more particularly to a reclosing carton having cover means enabling tight and positive closing of the carton after it has initially been opened.

Cartons, such as pasteboard boxes and the like, are frequently used in packaging small parts, powders, granulated material, and food items, such as breakfast foods. Ordinarily a carton of this sort is not emptied all at once. Instead, a portion of its contents is removed, and the carton is then used as a storage receptacle for the remainder of its contents. After opening, it is desirable to reclose the container, to prevent inadvertent spilling and spoilage of material, and to promote ease of stacking. If the material is a food item, closing a carton preserves the freshness of the food. The closure mechanism should not encumber opening of the carton, and it should be simple, practical, and capable of economic mass production.

Generally it is an object of this invention to provide closure means for a carton or box which takes care of the hereinabove set forth requirements in a highly practical and satisfactory manner.

It is a more specific object of the invention to provide in the top of a carton an openable cover portion, and a slideable locking member reciprocally mounted in a pair of elongated retainer slots formed in the carton top, the locking member being slideable to a locking position positively to lock the cover portion in a closing position.

According to an embodiment of this invention, the top of a carton is prepared in a conventional manner from a pair of rectangular cover tabs, each of which is joined along one edge to one of a pair of opposite sides of the carton. The tabs are folded over, with their inner edges overlapping, and then ordinarily adhered together using a conventional pasteboard adhesive.

A foldline is formed in each of the cover tabs and this foldline extends along the tab from one corner of the tab to its overlapping edge. The foldline accommodates folding of the corner of the tab outwardly from the top. The two tab corners, which constitute swingable flap portions, when folded away from the plane of the top, open up a V-shaped pouring spout in the carton top. The spout is sufficiently wide to enable quick flow of material from the carton, but somewhat constricted, so as to meter the flow of material and prevent the contents of a carton from falling out all at once. After use, the corner flaps may be folded back to close the carton.

Elongated slots are formed in the top parallel to the overlapping edges of the tabs, one on each side of the overlapping edges. A locking member with its ends inserted in these slots is slideable to and fro over the top. The locking member may be moved in covering relation over the corner flaps to hold them in a covering position.

Another object of the invention, therefore, is to provide in a carton top a pair of swingable, mating flap

2

portions swingable from a closed position to an open position, and a sliding member slideable from a release position wherein the flaps may be swung open to a locking position wherein the flaps are held in a closed, covering position.

Another object is to provide a locking construction which is readily incorporated in a conventional carton having a top prepared by folding over a pair of overlapping tabs integral with the side walls of a carton.

10 The invention is described hereinbelow in conjunction with the accompanying drawings wherein:

Fig. 1 is a perspective view illustrating top portions of a carton, and showing the top with the openable cover portions thereof in a closed position;

Fig. 2 is similar to Fig. 1 save that the locking member present in the construction has been moved to a release position accommodating opening of the openable cover portions; and

Fig. 3 illustrates the carton with the cover portions or flaps swung open, in the position they occupy when pouring material from the carton.

Referring now to the drawings, in the embodiment illustrated 10 indicates a conventional carton having a rectangular cross section. The carton has side walls 11, 12, a bottom wall (not shown), and a top wall 13. The carton is made of pasteboard or similar material, and may take various sizes and shapes depending upon the material packaged therein. The carton illustrated is of the type generally used for packaging breakfast cereals.

20 Top 13 of the carton is made by folding over a pair of cover tabs 16 and 17, each of which has a rectangular outline and is joined along a creaseline 15 to one side of the carton. The tabs are joined to opposite sides of the carton, and when folded over have inner edges 18, 19 which overlap each other.

Extending partially along the length of the carton top are a pair of parallel slots 21 and 22 which are usually weakened sections or partially severed. One of the slots is on one side and one of the slots is on the other side 40 of overlapping edges 18, 19. These slots are prepared to receive the opposite ends of an elongated slide or locking member 26.

45 Locking member 26 has a rectangular outline, and end edges 27, 28 parallel to the side walls of the carton and closely abutting these side walls. These end edges, by sliding against the inner faces of the side walls, keep the locking member from twisting about, and thus prevent inadvertent removal of member 26 from the slots. The locking member has an upturned tab 29 which functions as a handle when moving the locking member back and forth. The locking member is slidably mounted for movement between a released position shown in Figs. 2 and 3, and a locking position shown in Fig. 1.

50 Formed one in each of the tabs, and extending from one set of adjacent ends of creaselines 15 toward the center of the carton top, are a pair of foldlines, indicated at 31, 32. These foldlines extend obliquely across corners of tabs 16, 17 and intersect edges 18, 19 at 55 intersection points 33, 34. Each foldline and corner edge portion of the tab it extends across define a triangular-shaped, cover flap portion. These are indicated for the tabs at 36, 37.

When the carton is sealed for shipment, the tabs 16 and 17 are folded over the top of the carton, and fastened together using an adhesive deposited in the area between the overlapping edges of the tabs. The tabs may be fastened together along their entire length, or just along their length in the space between intersection points 33, 34 and the adjacent set of ends of creaselines 15 located away from foldlines 31, 32. If fastened along their entire length, the carton is initially opened

by inserting a knife or other sharp instrument into the glue line between the tabs, and running the knife along the glue line from intersection points 33, 34 downwardly over flaps 36, 37.

During use, when it is desired to open the carton, locking member 26 is slid to the release position shown in Fig. 2. Flaps 36 and 37 are then swung outwardly by bending them along foldlines 31, 32 to the position shown in Fig. 3. Many cartons are also provided with inwardly extending side flaps, such as side flap 39, which may be swung open to the position shown in Fig. 3. The presence of side flap 39 is not essential.

After the flaps are fully swung open, the usual paper liner of a breakfast cereal package is exposed, which may be ripped open to enable pouring of the carton contents.

As can be seen in Fig. 3, the flaps or cover portions when swung open define a V-shaped pouring spout or opening. The opening is large enough to allow the contents of the box to pour out easily. The opening is directly adjacent side wall 11, so that no lip or shoulder is present at the bottom of the spout to catch or hold back material pouring from the box. Thus the box is easily emptied completely.

When the opening is closed, as shown in Fig. 1, member 26 may be slid downwardly to a locking position, wherein a central portion of member 26 covers the overlapping but separable edges of the flaps, and firmly holds the flaps in a covering or closing position.

This results since the partline of the upper flap 36, i.e., the line from which it is separable from the remainder of the top, is disposed intermediate slots 21, 22 and is covered by member 26 when the latter is in a locking position.

It will be noted that the construction is readily incorporated with existing type boxes utilizing folded over cover tabs to make up the top of the box. The construction requires the addition of only one extra part, exemplified by sliding locking member 26, which may be formed as a part or all of tab 39.

It is claimed and desired to secure by Letters Patent:

1. A carton having side walls, a top and a bottom wall forming an enclosed container, a pair of elongated slots lying side-by-side formed in said top wall, and a slide portion having opposite ends inserted through said slots slidably mounted on said top for movement therealong between release and locking positions, said slide portion having a central portion intermediate its ends carried outwardly of said top, said top having an operable cover portion separable from the remainder of the top along a partline disposed intermediate said slots, said partline being covered by the central portion of said slide portion when occupying its locking position.

2. A carton having side walls, a top and a bottom wall forming an enclosed container, said top having a cover flap adjacent one of said side walls separable from the remainder of the top, a pair of elongated slots lying side-by-side formed in said top, said cover flap separating from the remainder of said top along a partline spaced between said slots, and a slide portion having opposite ends inserted through said slots slidably mounted on said top for movement therealong between release and locking positions, said slide portion having a central portion intermediate its ends carried outwardly of said top, the central portion of said slide portion covering said partline when occupying its locking position.

3. A carton of rectangular cross section having side walls and four cornered top and bottom walls forming

an enclosed container, said top having a pair of flaps swingable about foldlines extending from adjacent corners of the top inwardly toward the center of the top, said flaps swinging from a closing position closing off the interior of said carton to an opening position opening up the interior of said carton, each of said flaps terminating in an edge extending lengthwise along the top intermediate the sides thereof with the edges of the two flaps progressing lengthwise between the same two sides, a pair of slots formed in said top lying side by side and with one on one side and one on the other side of said edges, and a slide portion having opposite ends inserted through said slots slidably mounted on said top for movement therealong between release and locking positions, said slide portion having a center portion intermediate its ends carried outwardly of said top, said center portion covering said edges when occupying its locking position.

4. A carton of rectangular cross section having side walls and four cornered top and bottom walls forming an enclosed container, said top having a pair of flaps swingable about foldlines extending from adjacent corners of the top inwardly toward the center of the top, said flaps swinging from a closing position closing off the interior of said carton to an opening position opening up the interior of said carton, said flaps each having a triangular configuration and a terminal edge along one side which is adjacent the terminal edge of the other when the flaps occupy a closing position, a pair of slots formed in said top lying side-by-side and with one on one side and one on the other side of said terminal edges, and a slide portion having opposite ends inserted through said slots slidably mounted on said top for movement therealong between release and locking positions, said slide portion having a center portion intermediate its ends carried outwardly of said top, said center portion covering said terminal edges when occupying its locking position.

5. In a carton having side walls and a rectangular four cornered top, said top being formed by a pair of rectangular tabs, each joined through a creaseline along one edge to a side wall of said carton, the tabs being joined to opposite side walls of said carton, the edges of said tabs opposite said creaselines overlapping each other, the improvement comprising a pair of slots formed in said top, one on one side and one on the other side of said overlapping edges, a pair of foldlines formed in said tabs, one in each tab, extending from one set of adjacent ends of said creaselines to the overlapping edges of said tabs and intersecting these edges, and a slide portion having opposite ends inserted through said slots slidably mounted on said top for movement therealong between release and locking positions, said slide portion having a center portion intermediate its ends carried outwardly of said top, said center portion covering said overlapping edges and foldlines when occupying its locking position.

6. The carton of claim 5 wherein said foldlines intersect said overlapping edges at intersection points spaced a substantial distance inwardly from the carton side wall next to the other set of adjacent ends of said creaselines, and wherein said tabs are adhered together along their overlapping edges in the space between the side wall next to said other set of adjacent ends and said intersection points.
